UNITED STATES PATENT OFFICE.

WILLIAM P. WHITE, OF BROOKLYN, NEW YORK, ASSIGNOR TO ANCHOR CAP & CLOSURE CORPORATION, OF BROOKLYN, NEW YORK, A CORPORATION OF NEW YORK.

METHOD AND DEVICE FOR CONTROLLING PRESERVING APPARATUS.

1,385,599.

Specification of Letters Patent. Patented July 26, 1921.

Application filed April 9, 1919. Serial No. 288,725.

To all whom it may concern:

Be it known that I, WILLIAM P. WHITE, a citizen of the United States, residing at Brooklyn, in the county of Kings, State of New York, have invented certain new and useful Improvements in Methods and Devices for Controlling Preserving Apparatus, of which the following is a specification.

This invention relates to a method and an apparatus for use in preserving food-stuffs and the like, and has particular reference to a method and an apparatus designed for use in the processing of food-stuffs packed in individual containers and sterilized under a heat applied to the outside of the containers.

Under present practice in the processing of food-stuffs packed in containers it is customary, while subjecting the container to a sterilizing heat, to subject it also to an exterior fluid pressure within the retort or apparatus in which it is being treated, for the purpose of counteracting or equalizing the internal pressure developed by the sterilizing heat. This is necessary in order to prevent bursting, swelling or distortion of the containers, or the forcing of the closures of the containers, by the internal pressure.

Experience has demonstrated that there is a wide variation in the amount of pressure developed within containers during the processing. This is due not only to the different degrees of heat which must be utilized with different food-stuffs, but also to the nature of the different food-stuffs themselves, some products developing pressures greater than others, and some products developing pressures more rapidly than others. Attempts have been made, through experimentation, to lay out in empirical tables the proper temperatures and external pressures required by different food-stuffs, but data compiled in this form are only relative and approximate, due to the variation in pressure developed by different lots of the same sort of food-stuffs. As a result, the regulation of the processing pressure remains, in present practice, largely a matter of guess or estimation, the accuracy of which varies with the individual, and the results of which entail losses through bursting, leaking, or distorted containers.

Inasmuch as the internal pressure developed in the food containers during the

progress of the process varies over a wide range, first rising as the sterilizing temperature is raised, and then falling, as the containers are cooled, it necessarily follows that the regulation of the equalizing pressure must be continuous, and must follow immediately the sometimes slow and sometimes rapid changes of pressure within the containers and in the retort exterior of the containers.

It is the object of my invention to provide a method for the regulation of the equalizing pressure within the processing retort whereby the external or equalizing pressure imposed upon the containers will be automatically varied immediately and in the proper proportion to meet all variations in the internal pressure of the containers. It is a correlative object of my invention to provide a novel apparatus whereby this method of regulation may be put into effect.

A further object of my invention is to provide such a method and apparatus whereby the regulation of the equalizing pressure is independent of human agency, thus eliminating the inaccuracy and uncertainty arising from estimation and the lack of uniformity of human skill.

A further object of my invention is to provide such a method and apparatus, the range of application of which is unlimited, as to the diversity of products on which it may be employed.

More specifically stated, the object of my invention is to provide a method and apparatus in which the condition of the container itself while undergoing the processing is the initiating factor in accomplishing regulation of the equalizing pressure.

Still more specifically stated, my method and apparatus involves the utilization of a specimen container from the lot which is being processed to accomplish the regulation of the external pressure in accordance with the requirements imposed by the internal pressures developed in the specimen container during the sterilizing process.

Other and further objects of my invention will be obvious or pointed out herein, reference being had to the accompanying drawings, wherein is illustrated one of the forms in which the invention may be practised and certain of the wide variety of devices by which the method may be carried into

effect. It will be understood that the arrangements shown in the drawings and hereinafter described are given as illustrative of the invention merely, and do not attempt 5 to portray the limits of its embodiments.

In the drawings Figure 1 represents a fragmentary diagrammatic illustration of a portion of a processing retort with certain of its adjunct controlling apparatus, illustrating 10 the application of my invention;

Fig. 2 is a top or plan view, partly in section, of one form of device constituting one 15 of my present inventions;

Fig. 3 is a sectional view taken approximately on line 3—3 of Fig. 2;

Fig. 4 is a diagrammatic detail in the nature of a section through the controlling valve mechanism of the device illustrated in Fig. 2;

20 Fig. 5 is a diagrammatic detail view illustrating a form of control valve.

Referring to these illustrations in detail, by means of the reference numerals it will be understood that the numeral 10 designates 25 generally a processing retort suitable for use in the processing of food-stuffs in sealed containers, which may be of the sort illustrated in the patent to Luhrmann and Magrane, #1,194,252 granted May 23, 1916. This retort is fed by a steam inlet pipe 11 coming 30 from a suitable source of hot steam supply, the admission of steam from this source being controlled by a valve 12. The retort is also fitted for the introduction of a pressure fluid, such as compressed air, which 35 may be by way of the pipe 14 illustrated, the same being fed from a suitable compressor or fluid pressure storage. Admission of the pressure fluid may be controlled by a suitable valve, as 15. It is immaterial, of course, so far as my present invention is concerned, whether or not the steam and the pressure fluid are mixed before introduction into the retort, or introduced separately, it being 40 simply necessary that they be subject to independent control. The numeral 16 designates a suitable safety valve operable at a predetermined maximum pressure. Numeral 17 designates containers of food-stuffs 45 disposed in the retort for subjection to the processing. As is well known in the art, the containers of food-stuffs having been deposited in the retort, and the retort closed, the retort is subjected to the sterilizing heat 50 introduced through the pipe 11, whereby the temperature within the retort is raised to the proper degree. It is also to be understood that the fluid pressure supplied by way of the pipe 14 is such that a suitable excess 55 pressure may be built up within the retort exterior of the containers therein to prevent distortion, breakage or uncapping of such containers by the pressure developed within them due to the sterilizing or cooking temperature. By means of a pipe 18 fed from 60

a suitable pressure source cooling fluid, such as cold water, may be introduced within the retort for the purpose of reducing the temperature of the containers and their contents upon the completion of the sterilizing or 70 cooking operation.

It will be obvious, that as the temperature of the contents of the containers is increased by the introduction of the heating fluid, the pressure developing within them internally 75 will increase. It is likewise obvious that when the cooling fluid is introduced within the heated retort, there will be a very sudden fall of pressure within the retort exterior of the containers, due to the sudden drop in 80 temperature, before the contents of the containers has had time to cool. Inasmuch as the contents of the containers is not cooled so quickly as the air or other fluid surrounding them, the internal pressure of the containers will not be reduced in proportion to the external pressure. This would cause a sudden unbalancing of the internal and external pressures, which would be likely to result in distortion of the containers or forcing of their closures. To meet these variations between the pressures within the containers and the pressures to which they are externally subjected, it is necessary to accomplish the regulation of the fluid pressure 85 controlling means.

During the processing of the containers and their contents, as the temperature of the contents is raised and the pressure is developed within the containers, pliable portions of the containers will be flexed or moved more or less by the variation in pressure. In most instances the containers, when their contents are packed, are sealed under a vacuum. Whether the containers 100 themselves are of metal, or whether they are of glass sealed with metal caps or other pliable material, this sealing under a vacuum has the effect of forcing slightly inwardly the unsupported portions of the caps, 105 so that they are somewhat concave externally. The development of internal pressure within the containers as the temperature of their contents is raised, therefore, would first tend to take up this concavity by flexing the metal of the caps outwardly, and if unopposed by external pressure, would still further flex the caps to a condition where they would be convex externally, or even forced or moved from their seats. By the 110 introduction of suitable fluid pressure within the retort exterior of the container the outward flexion of pliable portions or displacement of the caps may be limited.

By my invention I render the supply of 115 fluid pressure necessary for counteracting the initial pressure, and its regulation, dependent directly upon the condition of a container subjected to all of the influences present within the retort. For this purpose 120

I provide an apparatus such as that designated by the numeral 19, and illustrated more in detail in Figs. 2 and 3. This apparatus is in the nature of a body member or 5 holder having end portions 20 and 21 connected by side rails or bars 22, the internal dimensions between the end members and between the bar members being such as to accommodate containers of the sizes which 10 it is intended to subject to the preserving process. The arrangement of said end and bar members is such as to provide a retainer or cradle for one of the containers. Upon the end member 20 is adjustably mounted a 15 platform or base 24, which may be moved as by means of the screw 25, to accommodate containers of different sizes between it and the opposite end member 21. The end member 21 may provide the mounting for 20 a suitable valve or controlling device 26, the details of which are illustrated in Figs. 4, 5, and 6. The end member 21 may also form a mounting for a spring 27, which carries a ring or contact member 28 adapted 25 to engage one end of the container moved thereagainst by adjustment of the base member 24. Such a container is designated by the character C, and may be either a tin can, or a glass container sealed with a 30 cap K.

As illustrated in Fig. 4, the control device 26 may be in the nature of a valve arrangement in which the valve member 29 has a stem 30 extending through the end member 35 21 to a proper position to make contact with the surface of the cap or end closure K of the specimen container mounted and held between the ring 28 and the support 24. The valve 29 controls a pressure line 31, the 40 supply side of which is furnished with fluid pressure from a suitable source and the exhaust side of which is operative upon a pressure responsive device 32 arranged as an actuator for the valve 15 which controls the 45 supply of pressure fluid. The arrangement is such that the opening of the valve 29 effects the operation of valve 15 to admit fluid pressure to the retort 10.

In actual operation, when the retort 10 is 50 filled with containers of food-stuff to be processed, one of the containers typical of the lot with which the retort is charged, is placed in the device 19, suitable adjustment of the member 24 being accomplished to position a pliable or movable portion of the 55 container, such as the metal of a cap K, in operative association with the extremity of the valve stem 30, the container being supported in this fashion by contact with the 60 resiliently held ring 28, and the base members 22. The valve 29 is held seated by the fluid pressure in line 31, or by spring pressure, the position of the container C being regulated to permit the valve 29 to remain 65 seated while the container is in its normal condition. The holder 19 with the container mounted therein is disposed in the retort along with the other containers to be processed, and the retort is closed and the sterilizing or cooking heat introduced into it. 70 Upon the heat becoming effective upon the contents of the containers in the retort to produce internal pressure within them, pliable or movable portions of the containers will be under the tendency of moving outwardly. This will be true of the pliable or movable portion of the specimen container C associated with the valve stem 30, as container C is typical of the other containers, both as to structure and contents. Upon a 75 predetermined amount of expansion or movement of the pliable or movable portion of the container associated with the valve stem 30, the valve 29 will be unseated by the pressure of the expanding portion of the 80 container, permitting the operating pressure in line 31 to become effective upon the motor member 32, and open pressure valve 15. This will admit fluid pressure to the retort which will immediately become effective 85 externally of the containers, including container C, to oppose the internal pressure causing this expansion of portions of the containers. This increase of pressure within the retort will be continued to the point 90 where the expansion of the container has been counteracted, and the expanded portion moved back to a predetermined position. When such readjustment of the container is accomplished, the valve 29 thereby will be 95 permitted to seat, whereupon further increase of pressure within the retort 10 will be stopped by the resulting closing of the pressure valve 15. In this fashion, expansion of the containers from internal pressure 100 will be immediately met by a readjustment in the external fluid pressure so that the possibility of the containers being ruptured or distorted, or their closures forced, by the 105 internal pressures, will be automatically prevented. In the same manner, when the cooling fluid is admitted to the retort, the sudden drop in external pressure within the retort would permit an alteration in position or form of pliable or movable portions of 110 the containers under the remaining internal pressure, which alteration on the part of the specimen container C would result in the unseating of valve 29 in the manner above described, and the consequent increase of the 115 fluid pressure within the retort external of the containers to the point where it would have the proper excess over the internal pressure in the containers and move the altered portion of container C back to its predetermined normal position. The maximum 120 pressure valve 16 affords a limiting means for preventing pressure in the retort reaching a point where it would damage the containers, and the retort may be bled or vented, 125 130

as may become desirable during the cooling operation, by means of a vent cock 34.

The supply of heat to the retort is preferably under automatic control. A suitable 5 heat responsive device, such as the thermostat 35, is effective upon a suitable regulator 36 to control the admission of heating fluid by means of the motor device 37 which operates the valve 12. Admission of heating 10 fluid during the cooling operation is prevented by closing of the hand operated valve 38 in the steam line.

From the foregoing description of my improved regulating process it will be observed 15 that it resides in regulating the admission of fluid pressure into a retort by means of one of the containers which is being subjected to the preserving process.

In Fig. 5 is illustrated a form in which the 20 regulating valve may be embodied. The nipples 50 form attachments for the terminals of the pressure line 31, and the ball 51 forms the valve which seats under the pressure. The valve operating rod 52 has its 25 outward movement limited by a stop 54, and is seated in a suitable gland or packing 55 which prevents admission of the pressure from the retort to the controlling valve. The outer extremity of the operating rod 52 is 30 disposed for coöperation with the specimen container.

The necessary connections for the device 19 may be made by means of flexible tubing such as flexible metal pressure hose let out 35 through a suitable gland in the wall or cover of the retort. While the mounting of the container holder is not limited to such, this sort of arrangement facilitates its handling and manipulation as well as its placing in 40 the retort along with the other containers.

By means of the method and apparatus above described regulation of the pressure within the retort is rendered entirely automatic and independent of human agency, 45 it being necessary to provide simply the correct initial adjustment of the specimen container in the holding device at which adjustment the container is retained, expansion of the device 19 by heat being compensated 50 for by suitable means such as the follower spring 43. Moreover, the use of this method and apparatus entirely eliminates any estimation or speculation as to the necessary pressure for the particular goods in process, 55 as the proper pressure is automatically supplied and is governed by the particular changes in the container which the use of the pressure is designed to inhibit or counteract.

Having thus described my invention, what I claim is—

1. In the art of preserving, the method residing in subjecting sealed packages to influences which tend to modify their structural form, and regulating the application 65

of said influences by structural modifications of a package subjected thereto.

2. In the art of preserving, the method of regulating the treatment of packages within a processing retort, which consists 70 in applying fluid pressure externally to the packages and controlling the application of such fluid pressure by structural alterations effected in a container by the processing.

3. In the art of preserving, the method of processing comprising applying fluid pressure externally to sealed packages while applying to a specimen package physical influences accruing during the preserving process and controlling the application of 80 fluid pressure by alterations in said container induced by such influences.

4. In the art of processing sealed food packages, a method which comprises disposing the packages in a retort, inducing fluid 85 pressure in the retort, and controlling the induction of fluid pressure by structural alterations of a package in the retort.

5. In the art of processing sealed packages under external pressure, the method 90 which resides in applying pressure fluid externally to the containers and controlling the application of said fluid by pressure from a wall of a container subjected thereto.

6. In the art of processing food packages, 95 a method which resides in the applying pressure fluid externally to containers and controlling the application of said fluid by flections of a portion of one of the packages subjected thereto.

7. In the art of processing sealed food packages, a method which resides in applying variable pressure externally to the containers and controlling the application of 105 said pressure by changes of position of a portion of a package subjected thereto.

8. In the art of processing food in sealed containers, the method which resides in subjecting sealed containers to heat and external fluid pressure and regulating the external fluid pressure by movement of a portion of a container occasioned by the heat. 110

9. In the art of processing sealed containers, the method consisting of subjecting the sealed containers to heat and external fluid pressure and regulating the application of fluid pressure externally to the containers by distortion of one of said containers. 115

10. In the art of processing capped containers, the method which consists of applying heat to the containers to modify their contents, and controlling the application of external fluid pressure to the containers by modification of the structural form of a 120 specimen container.

11. In the art of processing capped containers, a method of control comprising applying heat to the containers to modify their contents, applying fluid pressure to the con- 130

- tainers and regulating the application of fluid pressure externally to the containers by movement of a closure on one of the containers.
- 5 12. In the art of processing food packed in sealed containers, the method including applying heat to the containers to modify their contents, and controlling the application of fluid pressure to the containers by 10 movement of a cap of one of the containers subjected to such heat.
13. In the art of processing food in containers, the method including the applying of heat to the containers to modify their 15 contents and controlling the application of fluid pressure to the containers by structural changes produced in said containers by such application of heat.
14. In the art of processing sealed containers, the method consisting of the application of heat and fluid pressure to the containers and regulating the application of the fluid pressure by utilizing the changes of form of a container induced thereby.
- 25 15. In a preserving apparatus, a device for regulating the application of fluid pressure to containers, comprising means for supporting a specimen container, means for impressing fluid pressure on the exterior of 30 the container, and means operable by a portion of the container for controlling the operation of said last mentioned means.
16. In a preserving apparatus, the combination of means for heating a plurality of 35 containers, means for applying fluid pressure externally to such containers, and means operable by movement of a container to control the operation of said pressure applying means.
- 40 17. In an apparatus for processing food in containers, means for applying heat simultaneously to a plurality of containers, means for applying variable pressure simultaneously externally to such containers, and 45 means operable by flexion of a portion of a container to control the operation of the pressure applying means.
18. In an apparatus for processing material in containers, in combination, means 50 for heating a plurality of containers, means for applying fluid pressure externally to such containers, and means operable by expansion of a container for controlling the operation of such last mentioned means.
- 55 19. In an apparatus for processing material in containers, in combination, a retort, means for heating a plurality of containers disposed in the retort, means for admitting fluid pressure into the retort, a valve for controlling said last mentioned means, and an element operable by a container for operating said valve.
- 60 20. In an apparatus for processing material in containers, in combination, a retort, means for heating a plurality of containers in said retort, means for introducing fluid pressure into the retort, a valve for controlling said last mentioned means, and an element operable by movement of a portion of a container for operating said valve. 70
21. In an apparatus for processing material in containers, in combination, a retort, means for heating a plurality of containers in said retort, means for conducting fluid pressure into said retort, a valve for 75 controlling said last mentioned means, and an element operable by expansion of a container for operating said valve.
22. In an apparatus for processing material in containers, in combination, a retort 80 adapted to inclose a plurality of containers, means for conducting pressure fluid into the retort, and means operable by movement of a wall of a container for controlling the said last mentioned means. 85
23. In an apparatus for processing food packages, in combination, a pressure line, a valve for controlling the same, and means for mounting a food package with a wall portion in operative association with said 90 valve.
24. An apparatus for processing food packages, in combination a retort, means for introducing pressure fluid thereinto, controlling means for controlling the operation of 95 said last mentioned means, and means for supporting a food package with a pliable portion thereof in operative association with said controlling means.
25. In an apparatus for processing packages of food, a retort, means for introducing a fluid pressure thereinto, controlling means for governing the operation of said last mentioned means, and means for adjustably mounting a food package in operative association with said controlling means. 100
26. In an apparatus for processing packages of food, the combination of a retort, means for introducing fluid thereinto, controlling means for controlling the operation 110 of said last mentioned means, and means for adjustably mounting a food package in operative association with said controlling means.
27. In an apparatus for processing material in containers, in combination, a retort, means for inducing fluid pressure therein, and means operable by the wall portion of a container in the retort for varying the fluid pressure therein. 115
28. In a device for processing material in containers, in combination, a controlling valve, means for supporting a container in association therewith, and means for adjusting the supported container relative to the 120 valve.
29. In a device for processing material in containers, in combination, a controlling device, means for supporting a container in association therewith, and means for adjust- 125
- 130

ing the supported container relative to the controlling device.

30. In an apparatus for processing material in containers, in combination, means for supporting a container, a controlling device operable by the supported container, and means for effecting relative adjustment of the supported container and controlling device.

10 31. In a device for processing material in containers, in combination, a controlling device, supporting means for maintaining a container in operative association with controlling device, and means for adjusting said 15 supporting means to accommodate containers of different sizes.

32. In a device for processing containers, a holder for a container including end members, side members, regulating devices supported by one of said members, and means supported on another of said members for determining the position of a container relative to said regulating devices.

33. In a device for processing containers, 25 in combination, means for supplying fluid, a controlling device therefor, a member for operating the controlling device, and means for supporting a container with its closure in operative association with said member.

30 34. In an apparatus for processing food packages, in combination, a retort, means for supporting food packages within said retort, means for supplying fluid to said retort, a controlling device for said last mentioned 35 means, and means for supporting said controlling device in operative association with the closure of a food package within the retort.

35. In a device for processing food packages, in combination a controlling device, supporting means for maintaining a container in operative association therewith, and means to compensate for extension or contraction of the supporting means to 45 maintain the container in proper operative relationship with the controlling device.

36. In a processing apparatus, the combination of a receptacle adapted for the reception of a package, means for supplying fluid to the receptacle to affect a package therein, an actuating element operable by a commercial package in the receptacle, and a controlling device operable by the actuating element and effective to vary the supply of 55 fluid to the receptacle.

37. In a processing apparatus, the combination of a receptacle for the reception of packages, means for supplying fluid to packages within the receptacle, a controlling device for regulating the supply of fluid to the packages, and means operable by a commercial package within the receptacle to vary the operation of the controlling device.

38. In a processing apparatus, in combination with a receptacle for packages,

means for inducing opposing influences upon a package in the receptacle, a pressure operated device operable to vary the relationship of the opposing influences so induced, and an actuating member movable by the 70 container of a package within the receptacle for operating the pressure operated device.

39. In a processing apparatus, in combination with a retort, means for sustaining packages within the retort, a pressure operated device, an actuating member operable by the container of a package within the retort for controlling the operation of the pressure operated device, and processing means for inducing opposing influences upon 80 packages in the retort, one of said processing means being under control of the pressure operated device.

40. In a processing apparatus, the combination of a receptacle for a package, means for applying fluid to a package within the receptacle, a controlling device for regulating the operation of said last mentioned means, and a mechanical connection operably associating said controlling device with 90 a package within the receptacle.

41. In a controlling apparatus, the combination of a receptacle for a package, means for sustaining a package within the receptacle, means for supplying fluid to the receptacle, a controlling device for regulating the operation of the last mentioned means, an actuating element effective upon the controlling device, and a package associated with the sustaining means and operable to 100 move the actuating element.

42. In a processing apparatus, the combination of a retort, means for supplying fluid to the retort, a package in the retort, a controlling device for regulating the fluid supply, and a connecting member between the package and controlling device, said connecting member being movable by the package to operate the controlling device.

43. In a device for processing food packages, in combination, a receptacle for a package, means for supplying fluid to said receptacle, a controlling device for regulating the fluid supply, means for maintaining a package in the receptacle in effective association 115 with the controlling device, and means to compensate for variations in the supporting means to maintain the package in operative position.

44. In the art of preserving, a method 120 comprising the application of fluid to a package to modify its contents, and the regulation of the supply of fluid by the container comprising a portion of the package.

45. In the art of preserving, a method 125 comprising the application of fluid to a package and the regulation of the supply of fluid by flexure of the walls of the container comprising the incasing portion of the package.

46. In a processing apparatus, the combination of a receptacle adapted for the reception of a sealed package, means for supplying heat to the receptacle to heat the package therein, means for applying pressure externally to the package within the receptacle, a movable element operable by a package in the receptacle, and a controlling device operable by the movable element and effective to vary the pressure applied to the package within the receptacle.

47. In a processing apparatus, the combination of a receptacle adapted for the reception of a sealed package, means for supplying fluid to the receptacle to affect a package therein, a movable element operable by a package in the receptacle, and a controlling device operable by the movable element and effective to vary the supply of fluid to the receptacle. 15

WILLIAM P. WHITE.
